UNITED STATES PATENT OFFICE.

ERNEST M. WILSON, OF SEATTLE, WASHINGTON.

HEADLIGHT SCREEN AND REGULATOR.

1,176,120.

Specification of Letters Patent. Patented Mar. 21, 1916.

Application filed January 27, 1915. Serial No. 4,775.

To all whom it may concern:

Be it known that I, ERNEST M. WILSON, a citizen of the United States of America, and a resident of the city of Seattle, in the county of King and State of Washington, have invented certain new and useful Improvements in Headlight Screens and Regulators, of which the following is a specification.

10 My invention relates to screens intended for partially or wholly masking the intensity of the light emitted from a head light or other lamp used for illuminating purposes, in which the rays are concentrated 15 to be projected in one general direction.

The other object of my invention is to provide a screen or regulator by which the intensity of the projected rays may be varied as desired.

20 My invention is intended more particularly for application to the head lights of automobiles, although it is evident that it may be applied to head lights or other lamps intended for quite different use.

25 The novel features of my invention will be hereinafter defined in the claims which terminate this specification.

In the accompanying drawings I have shown my invention in the form of construction which is now preferred by me.

30 Figure 1 is a front elevation, mainly in section through the casing, of my device applied to a head light. Fig. 2 is a vertical sectional elevation taken at right angles to Fig. 1. Fig. 3 is a front elevation of my device showing the screen bars in their closed position, the front of the head light being removed. Fig. 4 is a vertical sectional elevation, taken at right angles to Fig. 3, 35 showing the upper set of screen bars in closed position and a portion of the lower set, the latter being in open position. Fig. 5 is a fragmentary horizontal section showing the manner of connecting the operating 40 cords with the screen bars. Fig. 6 is a perspective of one end of one of the screen bars. Fig. 7 is a perspective showing the device applied to the head lights of an automobile, and Fig. 8 is an elevation showing the detail of the crank arm by which 45 the two sets of screen bars are operated.

The object of this invention is to enable the driver of an automobile to control the intensity of the illumination produced by

the head lights, while remaining in his seat, 55 thus making it possible both to conform to municipal regulations, as to intensity of illumination, and also to vary this as it may be required by different conditions which may arise.

60 While the device is equally applicable to head lights which are otherwise employed, I will describe the same as applied to automobiles, its use upon other head lights being understood as being included therein.

65 Head lights of the character referred to are usually round in shape; I therefore provide a frame 1, which is of the same shape and adapted to fit closely within the forward part of the head light casing. In this 70 ring-like frame 1, are mounted a series of screen bars 2 and 20, these being essentially alike, but arranged as separate and independently movable sets. The set 2 extends across the upper portion of the head light 75 opening, while the set 20 extends across the lower half of the head light opening. Evidently the screen might be divided into more than two sets, if there were any reason 80 for this.

85 The material preferred for making these screen bars is glass. These may be of plain clear glass, or the glass may be frosted, colored, or provided upon one surface with either a screening coating which will intercept part or all of the light, or of a coating which is of a reflecting character, as silvering. Each end of each screen bar is secured within a pivoted member 22, which embraces the end of the bar and which has a 90 journal 23, adapted to enter the hole formed in the frame 1, or in lugs 10 which are secured to said frame. The screen bars of each set are connected by means of rods 3 which, in the form of construction shown, have off-set arms 30, which pivotally engage with lugs 31, secured to the screen bars, whereby all the bars of each set are caused 95 to move together and to occupy like angular positions. The two controlling bars 3, of the respective sets, are connected by a spring 32, which tends to draw them together, or into the position shown in Figs. 1 and 2, in which the screen bars extend substantially parallel with the direction of the projected light rays. While I have shown all of these bars as being parallel with each other in this position, it is evident that their 100 105 par-

allelism may be varied to whatever extent may be necessary to make them truly parallel with the projected light rays.

The pivot axis of one of each set of screen bars, as the axis 24, which lies nearest the center line of the head light, is extended through the casing and is provided, externally of the casing, with a crank arm 25, whereby the screen bars may be operated to turn them upon their pivots. These crank arms, in the arrangement of parts as herein shown, project each toward the other, whereby, when operated by a pull directed toward the rear of the head light, the screen bars will be turned in one direction for one set and in the opposite direction for the other set, that is, one set will be turned right handy, and the other set left handy.

The operating cords, or wires 4 and 40, are each connected with its respective crank arm 25, and are extended about guide pulleys 41, which are sufficient in number and so located as to carry these cords or wires, to the position from which it is desired to control the head light. This position, for an automobile, would be the controlling wheel thereof.

I have shown the screen bars as having their edges 21 beveled, so that when in the required position, as is shown in Fig. 4, the edges entirely overlap, thus forming a complete screen, which screen will entirely shut out the light, if the screen bars are made opaque. This is true of all of the screen bars excepting the edges which are outermost in each set, as for instance, the upper edge of the uppermost bar, the lower edge of the lowermost bar, and the edges of the bars of the two sets which meet. These latter bars, being the lowermost bar of the upper set and the uppermost bars of the lower set, turn in opposite directions and, as it is desired that the two sets be capable of independent movement, their meeting edges are made substantially square across.

By dividing the screen bars in two or more sets, it is possible to screen a part of the head light, leaving the other parts un-screened. In this way the upper half of the projected rays may be cut off while the other half is left in its normal brilliancy.

Stops 26 are provided which engage the operating crank arms 25, to limit their movement in each direction. It is desired that the edges of these screen bars shall never come in actual contact with each other, as, being made of glass the shock of contact would be liable to chip their edges. The use of the stops prevents this, while the beveling of their edges insures a complete interception of the light rays.

Having thus described my invention, what I claim as new, and desire to secure by

Letters Patent of the United States of America, is:

1. A headlight screen composed of pivoted screen bars, a plurality of controlling members, each connecting a series of the screen bars to move alike, and means for actuating said controlling members independently.

2. A headlight screen composed of pivoted screen bars, a plurality of controlling members, each connected with to control the angular position of a portion of said screen bars, one pivot axis of each set of screen bars having a crank arm thereon, and an actuating conductor extending from each of said crank arms to a controlling point.

3. A headlight screen comprising a frame adapted to be fitted to the headlight casing to encircle the emitted rays, a plurality of shutters or screen bars pivoted in said frame, a plurality of controlling bars each connected with its respective screen bars to cause them to swing together, one screen bar of each set having its pivot journal extending through the frame and the light casing and actuating means connecting each of said projecting journals with a distant point.

4. A headlight screen comprising a frame adapted to encircle the emitted rays, screen bars pivoted in said frame, a plurality of controlling bars, each connected with its respective screen bars to maintain them in like angular position, a spring connected to each of said controlling bars to thereby turn the screen bars into positions of approximate parallelism with the emitted rays, and means for actuating said controlling bars in opposition to said spring.

5. A headlight screen comprising a frame adapted to encircle the emitted rays, screen bars pivoted in said frame, a plurality of controlling bars, each connected with its respective screen bars to maintain them in like angular position, a spring connecting said controlling bars to thereby turn the screen bars into positions of approximate parallelism with the emitted rays, and means for independently actuating each of said controlling bars in opposition to said spring.

6. A headlight screen having a series of pivotal screen bars adapted to be turned into a common plane, means connecting said bars into independently operated groups, the outer edges of said bars which are outermost in each group being substantially square, the remaining edges being beveled to overlap when the bars are in closed position.

Signed at Seattle, Washington, this 20th day of January 1915.

ERNEST M. WILSON.
